UNITED STATES PATENT OFFICE.

RICHARD T. CRANE, OF CHICAGO, ILLINOIS.

AIR-HEATING FURNACE.

Specification of Letters Patent No. 27,530, dated March 20, 1860.

To all whom it may concern:

Be it known that I, RICHARD T. CRANE, of Chicago, in the county of Cook and State of Illinois, have invented a new and Improved 5 Air-Heating Furnace; and I do hereby declare that the following is a full, clear, and exact description of the same, reference being had to the annexed drawings, making a part of this specification, in which—
10 Figure 1, is a longitudinal vertical section of my invention taken in the line x, x , Fig. 3. Fig. 2, is a transverse vertical section of the same taken in the line y, y , Fig. 1. Fig. 3, is a horizontal section of the same, taken in 15 the line z, z , Fig. 1.

Similar letters of reference indicate corresponding parts in the several figures.

This invention relates to an improved air-heating furnace in which steam is employed 20 as a heating medium.

To enable those skilled in the art to fully understand and construct my invention I will proceed to describe it.

A, represents a chamber which may be of 25 rectangular form, the walls being of masonry and having an induction opening a , in its lower part and an eduction opening b , in its upper part. This chamber A, is the air-heating chamber and within it the fire-chamber, boiler, and steam pipes and steam chamber are placed.

B, is the fire-chamber and C, the boiler which encompasses the fire-chamber at its top rear and sides, the flues c, c' , passing 35 longitudinally through the boiler, one set of flues c' , being return flues and communicating with the lower end of the smoke stack D. The flues c, c' , are connected at the back part of the boiler by a chamber d. 40 The fire-chamber is placed directly over an ash-pit E, and the boiler C, may extend the whole length of the chamber A, but is not equal to it in width. The fire-chamber, boiler and flues may be of cast metal and 45 they are fitted at the lower part of chamber A, as shown plain in Figs. 1 and 2.

F, represents a series of vertical tubes which are attached to and communicate with the boiler C. These tubes communicate at 50 the upper ends with a chamber G, which extends the whole length of the chamber A, but like the boiler C, is not equal to it in width, see Fig. 2. The chamber G, may be of cast and the tubes F, of wrought metal. 55 The tubes F, are placed in parallel rows and the tubes of one row are placed in line with

the spaces between the tubes of the adjoining rows, as shown clearly in Fig. 3. The tubes F, are sufficiently high to place the steam chamber G, quite near the top of the 60 air-heating chamber A, the top of the latter being formed of a metal plate e.

From the chamber G, two horizontal pipes H, I, pass out through the chamber A, one at each side. The pipe H, communicates with 65 a metal bowl or vessel J, which is attached to the side of the chamber A. The bowl or vessel J, has an india-rubber top f, secured to it by a cap g, and on this india-rubber top an upright h, rests, said upright being attached at its upper end to a lever i, which has its fulcrum at j, a weight k, at one end and a cord or chain l, attached to the opposite end, said cord or chain having a valve m, attached to its lower end which valve 75 fits in the upper end of a pipe K, that leads into the ash-pit E, below the fire-chamber.

The pipe I, communicates with a bowl or vessel L, similar to J. The bowl or vessel L, is also provided with an india-rubber 80 top n, which is secured on the bowl by a cap o.

M, is a pipe the lower end of which passes into the ash-pit E, and the upper end passes into the bowl L, and extends up nearly to 85 the india-rubber top n. In the upper end of pipe M, a trilateral plug p, is fitted said plug being attached to a disk q, which has a stem r, that passes up through the rubber n, and has a cap or weight s, screwed on 90 its upper end.

The operation is as follows:—The boiler C, is supplied with a requisite quantity of water, (shown in blue tint Figs. 1 and 2,) and a fire is kindled in the fire chamber B. 95 Steam will soon be generated in the boiler C, in consequence of a great heating surface being presented to the fire-chamber. The steam fills the tubes F, and chamber G, and a large radiating surface is thereby obtained 100 in the chamber A, the air in passing up through said chamber A, being quickly heated to the temperature of the tubes and chamber G. By this arrangement or disposition of the tubes F, boiler C, and chamber G, the 105 air in passing through A, is brought directly in contact with the heating parts and passed between the tubes F, so that a large volume of cool air is quickly heated. The heated air may be conveyed from A, through any 110 proper tubes to the desired compartments and when the pressure of steam in the tubes

F, and chamber G, exceeds a certain point the pressure will raise the elastic top *f*, of the bowl J, the gravity of weight *k*, being overcome, and the valve *m*, will be depressed and the supply of oxygen to the fire diminished. By this means the device is rendered self-regulating. In case the pressure of steam in the tubes F, and chamber G, should become very great in consequence of a very quick fire the steam will raise the elastic top *n*, of the bowl L, and the disk *q*, will be elevated free from the top of the tube M, the plug *p*, serving as a guide, and the weight *s*, being overcome, the steam will rush down the pipe M, into the ash-box E, and extinguish the fire. The fire-chamber and ash-pit are provided with necessary doors and a door, *b*^x may be placed at the base of the smoke stack for the purpose of facilitating the cleaning of the flues and stack. Thus it will be seen that the device is rendered perfectly safe and also self-regulating and a large volume of air may

be heated with the smallest possible consumption of fuel.

25

I do not claim separately the employment or use of vertical steam tubes as heat radiators, nor do I claim any of the parts when viewed separately and irrespective of the end to be attained; but, having thus described my invention,

30

What I do claim as new and desire to secure by Letters Patent, is—

1. The combination with an air chamber A, and fire chamber B, of the boiler C, tubes 35 F, and steam chamber G, substantially in the manner and for the purposes described.

2. The combination with the fire chamber B, steam boiler C, tubes F, and steam chamber G, of the draft regulating and fire extinguishing devices described, substantially as and for the purposes set forth.
